UNITED STATES PATENT OFFICE.

JOHN F. GAIL, OF EVANSTON, ILLINOIS, ASSIGNOR TO SIMMONS COMPANY, OF KENOSHA, WISCONSIN, A CORPORATION OF DELAWARE.

MATTRESS-STITCHING MECHANISM.

Application filed July 7, 1921. Serial No. 482,900.

To all whom it may concern:

Be it known that I, JOHN F. GAIL, a citizen of the United States, residing at Evanston, in the county of Cook and State of Illinois, have invented certain new and useful Improvements in Mattress-Stitching Mechanism, of which the following is a specification.

My invention relates to improvements in 10 mattress stitching mechanism and relates more particularly to machines for inserting individual twine loops into a mattress for binding together portions of the filling or ticking or both. The purpose of inserting 15 said binding loops is to enable the mattress to maintain its proper shape.

My invention may be applied as an improvement on the general type of mattress tufting machine, such as is described in the 20 United States patents to Thompson, et al., No. 819,954, issued May 8th, 1906 and Mathewson, No. 1,193,708, issued August 8th, 1916.

In operating upon mattresses with the 25 machines of said prior patents, the knot which unites the ends of the length of twine forming each individual twine loop remains at the bottom of the mattress after a complete cycle of operations of the tufting 30 machine, and the short length of twine is left trailing from said knot. Also in cutting off the twine above the loop after the cycle of knot-tying operations has been completed, there is a section of twine, corresponding in length with the depth of the 35 loop, remaining in the mattress.

The principal object of my invention is to provide an improved process and apparatus for severing the twine adjacent the 40 knot, thereby eliminating wastage of the length of twine otherwise remaining in the mattress, while incidentally drawing the knot back through the mattress filling and thereby burying or concealing the loose end 45 of the knot inside the mattress.

This desirable result has been recognized in the art heretofore, as evidenced by U. S. Patents Nos. 1,211,924, 1,344,605 and 1,360,522. As in these three prior art patents my 50 invention has to do with the pulling of the knot up into the mattress portion prior to the final severing of the twine loop from a continuous twine supply.

In describing my invention for the purpose of securing a patent on the same, I

have illustrated it as applied to a Thompson mattress-tufting machine equipped with the knot tying mechanism of Mathewson.

In the drawings, accompanying this application,

Fig. 1 is a side elevation of a mattress tufting machine equipped with my invention.

Fig. 2 is a front or end elevation of the needle bar carrier and associate parts,

Fig. 3 is a section taken on the line 3—3 of Fig. 2,

Fig. 4 is a section taken on the line 4—4 of Fig. 2,

Fig. 5 is a section taken on the line 5—5 of Fig. 3,

Fig. 6 is a diagrammatic view showing certain parts of the knot-tying mechanism in the position occupied shortly after the completion of the first down stroke of the 75 needle,

Fig. 7 is a diagrammatic view showing the knot tying mechanism after the completion of the second down stroke of the 80 needle.

Fig. 8 is a section through the mattress portion showing the condition existing just after the commencement of the second upstroke of the needle, and

Fig. 9 is a view similar to Fig. 8 showing 85 the second upstroke of the needle completed and the twine ready to be severed.

In applying my invention to the Mathewson machine, substantially no change is necessary in the existing parts of the machine, except that, as described in the Patent No. 1,211,924 to Dillon, and Patent No. 1,360,522 to Gwizdowski, the cam which controls the releasing of the twine end after the knot has been formed, is suitably modified to permit the knot to be pulled up into the mattress upon the second upstroke of the needle. Inasmuch as such change can be made by any ordinary mechanic, I consider it unnecessary to describe such change 100 in detail.

In the Dillon patent the inventor apparently attempts to pull the knot back into the filling through the agency of the last upstroke of the needle bar. This would 105 necessitate the applying of very heavy tension to the spool which carries the supply of twine, or to a tension device which is interposed in the run of twine between the needle bar and the spool. It is of course 110

necessary to impose such tension or drag on the twine that the upward stroke of the needle will pull the knot through the bottom tick and up into the filling of the mattress, but this heavy tension, I have discovered leads into other difficulties. For instance, it is necessary at some time or other during the cycle of operations to pay out from the spool a sufficient amount of twine 10 to form a complete individual loop. In the Mathewson machine this paying out of the twine is partly effected on the first upstroke of the needle, after which the second downstroke of the needle effects a further paying out of twine, and there is also a certain length of twine paid out from the spool during the last upstroke of the needle.

With the heavy tension necessarily employed for pulling the knot up into the mattress after it has been tied, I find that it is an extremely difficult matter to pay out twine satisfactorily during the second downstroke of the needle. In this connection, it will be understood that in such paying out process on the second downstroke of the needle, the eye of the needle in effect operates as a sheave, but as a very inefficient one. Hence, a terrific strain is imposed upon the length of twine extending from the gripper to the eye of the needle. This strain may, in certain instances, have the effect of actually severing that portion of the tick which is located between the parallel branches of the loop. In any case, it has a tendency to bend or distort the needle and interfere seriously with the proper operation of the knot-tying mechanism. Also it makes it necessary to secure an extremely powerful grip on the end of the twine. In view of the above, it will be understood that one of the objects of my invention is to overcome the difficulties inherent in such a device as is attempted to be described in the Dillon patent.

My invention contemplates the use of a twine supply tension arrangement for pulling up the knot into the mattress together with means for so controlling the paying out of the twine that it will not be necessary to pay out any substantial amount of twine from the supply during the second downstroke of the needle. I secure this result by developing slack or excess length in the run of twine during the first upstroke of the needle or before the needle commences its second downward movement. My preferred method of effecting this result is to mount a suitable slack developing means on the upper portion of the machine, and preferably operable by the upward movement of the needle bar.

In the drawings, 10 represents the main frame of the machine which is equipped with the usual operating parts as disclosed 65 in the Thompson and Mathewson patents.

11 represents the supply spool from which the twine is paid out from time to time through an adjustable tension device 12. The run of twine intermediate the tension device 12 and needle 13 is carried through 70 suitable eyes or guides 14 and 15 fixed in the upper portion of the needle bar 16. Between the guide 15 and the needle 13 the twine passes around a set of three rollers, 17, 18 and 19, the rollers 17 and 19 being 75 stationary mounted on a suitable bracket 20 fixed to the front of the needle bar 16. The middle roller 18 is carried on the lower end 21 of a bell crank pivoted on a pin 22 also secured in the face of the needle bar 16. 80 The head of said pivot 22 is equipped with a suitable spring washer 23 which exerts a slight friction or drag on the pivotal movement of the bell crank.

The horizontal arm 24 of the bell crank 85 is equipped with a cam roller 25 which at certain times in the cycle is adapted to engage a cam 26 carried on the lower end of a pendent swinging arm 27. Said arm 27 is pivoted on a pin 28 fixed in the front of 90 the head 29 and is limited as to its outward swinging movement by a small stop which takes the form of a block 30 secured to the head as by a screw 31.

It will be understood that just prior to 95 the first downward stroke of the needle, the bell crank will be in the full line position as shown in Fig. 2, but elevated so that the cam roller 25 is above the swinging cam 26. In view of the fact that the swinging cam 100 can swing inwardly when it is engaged on its upper slope by the cam roller 25 as the needle bar descends, the cam 26 will swing inwardly and will drop back into its normal position shown in Fig. 2 after the cam roller 25 has wiped past the lower edge of said cam 26. Hence on the first downstroke of 105 the needle the bell crank will not rock on its pivot.

The first downstroke of the needle carries 110 the end 32 of the twine through the mattress portion and the protruding end is grasped by a gripper diagrammatically indicated at 33 in Fig. 6. On the first upstroke the roller 25 engages the cam 26 and as the needle bar rises, the bell crank will be thrown in the dotted line position shown in Fig. 2 thereby developing a bight in the twine intermediate the rollers 17 and 19. After the bell crank has been swung into the dotted line position 115 and has thus developed slack or excess length in the run of twine extending between the needle and the tension device 12, the bell crank will be held in its said rocked position by the spring washer 23 thereby causing the twine to remain taut and preventing it from falling away from the rollers 17 and 18, or becoming tangled.

Prior to the next downstroke of the needle, the needle bar is shogged or given an 120 125 130

outward movement in its carriage 34 by reason of the fact that actuating links 35 and 36 are moved longitudinally relative to each other. Said relative longitudinal movement 5 causes a pair of cam slots 37 in the cam bar 38 to push out the cam pins 39 which are mounted on inwardly extending tongues 40 fixed to the rear face of the needle bar 16. Fig. 5 illustrates the position of said parts 10 after the shogging action of the needle bar prior to the second downstroke of the needle.

It will be observed that when the parts are in the position shown in Fig. 5, the cam roller 25 has been moved outwardly into 15 such position that during the next reciprocation of the needle bar the bell crank will pass by, and will not be actuated by, the cam.

On the second downstroke of the needle, 20 in view of the fact that the end 32 of the twine is firmly grasped by the gripper 33 the twine will draw through the eye of the needle, and as the downstroke proceeds, the slack or excess length in the run of twine 25 caused by the dotted line position of the bell crank will be gradually taken up, the bell crank rocking back to its full line position, thereby eliminating the necessity of drawing off additional twine from spool 11 30 through the tension device 12.

At the conclusion of the second downstroke, the knot-tying instrumentalities and the needle will be in the condition shown 35 in Fig. 7, and when the needle makes its final ascent the knot will be tightened as shown in Fig. 8. At about the time that the needle is in the position shown in Fig. 8 the gripper 33 releases its hold on the end 32 of the twine so that the knot may be pulled 40 up into the filling of the mattress portion through the bottom tick 41. The knot is actually pulled up through the tick by the final portion of the upstroke of the needle bar, in conjunction with the tension or drag 45 imposed on the run of twine by tension device 12.

At the conclusion of the second upstroke when the parts are in the position shown 50 in Fig. 9, with the knot 42 and end 32 buried in the filling of the mattress, the twine is severed by a swinging cutter diagrammatically shown at 43 in Fig. 9. The needle bar then shogs back into the position shown in Figs. 3 and 4 and the machine is in 55 readiness for another cycle of operations.

In order to prevent undue slackness or kinks from developing in the run of twine below the guide 15, I may provide a tension device 44, which may be adjusted to press 60 lightly on the twine but at the same time impose no appreciable resistance during the paying out operation.

In view of the fact that the described 65 details of construction and operation are merely illustrative of a single application of my

invention, the scope thereof should be determined by reference to the appended claims, said claims being construed as broadly as possible, consistent with the state of the art.

70

I claim as my invention:

1. The process of inserting individual twine loops in a mattress, for tying together spaced surfaces thereof, which consists in (a) thrusting the end of a continuous twine completely through a portion of the mattress, (b) grasping the protruding end, (c) paying out twine to develop excess length in the run of twine intermediate its source and the end, (d) then, while arresting the paying out of the twine, thrusting an intermediate bight of the twine through the mattress portion at a point spaced from the first thrust, (e) knotting together the protruding parts of the end and bight to form a closed loop surrounding a portion of the filling, (f) pulling the knot into the filling, and (g) severing the twine intermediate the knot and source.

75

2. The process of inserting individual twine loops in a mattress, for tying together spaced surfaces thereof, which consists in (a) thrusting the end of a continuous twine completely through a portion of the mattress, (b) grasping the protruding end, (c) paying out twine to develop excess length in the run of twine intermediate its source and the end, (d) then, while arresting the paying out of the twine, thrusting an intermediate bight of the twine through the mattress portion at a point spaced from the first thrust, (e) knotting together the protruding parts of the end and bight to form a closed loop surrounding a portion of the filling, (f) increasing the length of twine 100 run between the source and the mattress portion and thereby pulling the knot into the filling, and (g) severing the twine intermediate the knot and source.

105

3. The process of inserting individual twine loops in a mattress, for tying together spaced surfaces thereof, which consists in (a) thrusting the end of a continuous twine completely through a portion of the mattress, (b) grasping the protruding end, (c) paying out sufficient twine from its source to form a complete loop, (d) then, while arresting the paying out of the twine thrusting an intermediate bight of the twine through the mattress portion at a point spaced from the first thrust, (e) knotting together the protruding parts of the end and bight to form a closed loop surrounding a portion of the filling, (f) pulling the knot into the filling, and (g) severing the twine intermediate the knot and source.

115

4. In combination, a needle bar, a needle, a twine supply, means for applying tension to the twine, means for actuating the needle bar to cause the needle to make a pair of re-

120

125

130

- 1 ciprocations in parallel spaced relation through a portion of the mattress, and thereby thrust through said mattress portion the end and an intermediate bight of the twine, 5 mechanism cooperating with the needle for knotting together the parts of the bight and of the end protruding from the mattress portion on the side remote from the needle bar and means for developing sufficient excess 10 length in the run of twine subsequent to the first thrust movement of the needle and prior to the second thrust of the needle whereby the necessity of drawing off twine through the tension device during the second 15 reciprocation of the needle is substantially avoided.
5. In combination, a needle bar, a needle, a twine spool, means for applying tension to the twine, means for actuating the needle 20 bar to cause the needle to make a pair of reciprocations in parallel spaced relation through a portion of the mattress, and thereby thrust through said mattress portion the end and an intermediate bight of the twine, 25 mechanism cooperating with the needle for knotting together the parts of the bight and
- of the end protruding from the mattress portion on the side remote from the needle bar and means for developing sufficient excess length in the run of twine subsequent to the first thrust movement of the needle and prior to the second thrust of the needle whereby the necessity of drawing off twine through the tension device during the second reciprocation of the needle is substantially avoided, the arrangement being such that during a portion of the final upstroke of the needle, the run of twine between the knot and the source will be tensioned sufficiently to pull the knot into the interior of the mattress.
6. In a machine of the class described, the combination of knotting mechanism, a needle adapted to make a pair of reciprocations through a mattress portion and cooperating with the knotting mechanism to form a knotted twine loop surrounding a portion of the mattress filling and mechanism operating only during the first upstroke of the needle for paying out substantially enough twine to form a complete tied loop.

JOHN F. GAIL.
